UNITED STATES PATENT OFFICE.

WAYNE H. WORTHINGTON, OF BATTLE CREEK, MICHIGAN, ASSIGNOR TO ADVANCE-RUMELY COMPANY, OF LA PORTE, INDIANA, A CORPORATION OF INDIANA.

HULLER.

Application filed March 20, 1925. Serial No. 16,875.

This invention relates to a separator and huller and particularly to a separator adapted for the hulling of beans. It has for one object to provide a machine in which 5 stones, dirt and foreign matter generally will be automatically removed from the material before it reaches the separating zone. Thus the impurities are separated out from the material which passes through the machine, and the machine itself is freed from foreign matter which might damage it or cause clogging or unsatisfactory operation of the machine itself. Another object is to provide a machine in which the foreign 10 matter separated out from the material as it passes toward the final separating zone is thrown out of the machine entirely. Other objects will appear from time to time throughout the specification and claims.

20 My invention is illustrated more or less diagrammatically in the accompanying drawings, wherein:

Figure 1 is a vertical longitudinal section of a portion of the machine showing the 25 stone picker mechanism and associated parts.

Figure 2 is a side elevation of that portion of the machine;

Figure 3 is a side elevation similar to 30 Figure 2 showing the reverse side of the machine and particularly showing the driving connection.

Like parts are indicated by like characters throughout.

35 A represents generally the housing which encloses the mechanism. B is the enclosing and supporting housing within which a conveyor preferably of the belt type is mounted and which conveys the material to the separating zone. C is the belt conveyor provided with slats or cleats C¹. It revolves at one end about a pulley C² which is carried upon a shaft C³. C⁴ is a floor beneath the belt. C⁵ is an extended covering member which 40 forms in effect an extension of the floor C⁴ and is curved about the shaft C³. It serves among other purposes to prevent material which is brought in on the conveyor from falling down and escaping the stone picker 45 drum.

D is a shaking pan. Its lower end is slidably mounted on the plate D¹ and adjacent its upper end it is engaged by one or more rocker arms D² carried on the rock shaft 50 D³ which is journaled in bearings D⁴ on the

separator frame. D⁵ is a lever arm which is attached to the rock shaft D³ and connected at its free end to a pitman D⁶ which is carried upon a crank pin secured in the pulley D⁷ on a shaft D⁸. The pulley and shaft 55 are driven in a manner which will be described below.

E is a concave provided with removable teeth E¹ and in co-operation with it is the cylinder F mounted on a shaft F¹ which carries at its outer end a driving pulley F² adapted to be driven by the belt F³ from any suitable power source. Mounted in the cylinder F are removable teeth F⁴. The details of the concave and its associated 60 parts will not be described further as they form no part of the present invention. F⁵ is an additional driving pulley mounted on the shaft F¹ and adjacent to the pulley F². At the opposite end of the shaft is a third 65 belt pulley F⁶.

Mounted above the shaker pan on a shaft G is a stone picker cylinder G¹ provided with teeth G² which may be removable and are preferably rearwardly bent as shown. 70 The shaft G carries at its outer end a belt pulley G³ which is in contact with and driven by a belt N.

H is a beater carried on a shaft H¹. It is mounted behind and slightly above the 75 stone picker cylinder and generally above the cylinder F. The shaft H¹ carries at one end a belt pulley H². Between the pulley H² and the pulley D⁷ on the shaft D⁸ is a crossed belt H³. On the shaft H¹ at the 80 opposite end from that which carries the pulley H² is a second belt pulley H⁴.

I is a belt tightening pulley carried in an arm I¹ which is pivoted at I² and provided with a handle extension I³. The arm is 85 positioned adjacent to a quadrant I⁴ provided with a locking nut I⁵ by means of which it may be locked in fixed position with relation to the quadrant.

Between the carrier and the stone picker 90 cylinder and slightly below the carrier is a shield J. This shield runs transversely across the machine throughout substantially the width of the carrier. It may be flexible and under certain circumstances the members C¹ of the carrier will strike it and deflect it slightly downward, and it is to permit this that it is generally preferably flexible. It is removably fastened to a transverse member J¹. K is a deflector plate 95

situated in the upper part of the machine. It is preferably metallic.

L is a stone receiving compartment having an open side L¹ in which is hung a swinging curtain L², preferable flexible. In the top of the compartment L is hinged a cover L³. The compartment L has in its bottom, raised slat members L⁴. M is a swinging cover for a portion of the main 10 casing which may be raised for inspection purposes and to permit entrance into the machine for repairs and other purposes.

N is a belt which is mounted about the pulleys F⁶, H⁴, G³ and I. O is a sprocket 15 on the carrier shaft C³. O¹ is a sprocket pinion on the shaft D⁸, and O² is a chain about the two sprockets by means of which the carrier shaft is driven from the shaft D⁸. O³ is a chain tightening sprocket pinion 20 adjustably mounted at O⁴.

P is a flexible downwardly depending curtain mounted at the mouth of the machine and depending downward toward the carrier belt and into the normally entering 25 path of the material which is carried thereby. When material is being fed to the machine this material is frequently deflected rearwardly. During the operation of the machine any material which may be driven 30 toward the feeding opening of the machine will strike the curtain and will be deflected by it downwardly and be prevented from flying out of the machine.

Although I have shown an operative device, still it will be obvious that many changes might be made in size, shape and arrangement of parts without departing materially from the spirit of my invention; and I wish, therefore, that my showing be 40 taken as in a sense diagrammatic. Particularly where in the specification and claims I have used the word "grain" I mean grains of any sort. It might be wheat, oats, beans or any material which in growth is associated with pods, chaff, stalks and other matter 45 from which it must be separated.

The use and operation of my invention are as follows:

When the machine is to be used, the mechanism 50 is set in operation and material is placed upon the feeder and by it carried toward the feed opening. Material passes off of the feeder carrier and against the stone picker cylinder. The teeth of this cylinder contact stones, lumps of dirt and other foreign matter and drive them upwards against the deflecting plate K and from this plate they are deflected against the upper curtain which hangs in the door way of the 55 chamber L. The heavy material swings the curtain and passes into the chamber, and lighter material fails to swing the curtain and drops downward again into the machine and is carried forward toward the hulling 60 and separating zone.

Some material will be deflected outward toward the feeding opening and would be driven out of the machine. To prevent this the curtain P is hung in the opening and material driven toward the feeding opening 70 strikes the curtain and is deflected by it downward and drops into the stream of material coming into the machine and is prevented from flying from the machine. Thus means are provided both for separating foreign matter from the material to be hulled and separated, and for preventing the accidental discharge of material from the machine by reason of the action of the stone picker. 75

All remaining material is, of course, caught by the stone picker cylinder and carried upward and over, and thrown in the direction of the beater. The beater strikes this material and forces it downward again 85 toward the concave and the threshing cylinder which co-operates with it. The beater also sets up an air current which further blows and diverts material downward toward the concaves and the threshing zone. 90

The driving mechanism operates as follows:

The main cylinder shaft F¹ is driven from any suitable power source. From this shaft the beater shaft, and the stone picker shaft 95 are driven. From the beater shaft H¹ the shaft D⁸ is driven and from the shaft D⁸ the carrier shaft C³ and the shaker pan D are driven.

I claim:

1. A stone picker, adapted to remove foreign material from the stream of grain, which includes a rotating member mounted in the path of the grain and adapted, as it is rotated, to drive the foreign material from 105 the stream of grain, in combination with a beater adapted to drive the grain raised by the stone picker downward, and a yielding closure mounted in and partially closing the opening through which the grain is introduced. 110

2. In combination with a separator, a stone picker, adapted to remove foreign material from the stream of grain, which includes a rotating member mounted in the 115 path of the grain and adapted, as it is rotated, to drive the foreign material from the stream of grain, in combination with a beater adapted to drive the grain raised by the stone picker downward, and a yielding closure mounted in and partially closing the 120 opening through which the grain is introduced.

3. A stone picker, adapted to remove foreign material from the stream of grain, 125 which includes a rotating member mounted in the path of the grain and adapted, as it is rotated, to drive the foreign material from the stream of grain, and a yielding closure mounted in and partially closing the opening 130

- through which the grain is introduced, and a receptacle adapted to receive the foreign matter driven from the grain, said receptacle having an open side closed by a yielding member adapted to be struck by such material and moved thereby to permit the material to enter the compartment.
4. A stone picker, adapted to remove foreign material from the stream of grain, which includes a rotating member mounted in the path of the grain and adapted, as it is rotated, to drive the foreign material from the stream of grain, in combination with a beater adapted to drive the grain raised by the stone picker downward, and a yielding closure mounted in and partially closing the opening through which the grain is introduced, and a receptacle adapted to receive the foreign material driven from the grain, said receptacle having an open side closed by a yielding member adapted to be struck by such material and moved thereby to permit the material to enter the compartment.
5. In combination with a separator, a stone picker adapted to remove foreign material from the stream of grain, which includes a rotating member mounted in the path of the grain and adapted, as it is rotated, to drive the foreign material from the stream of grain, in combination with a beater adapted to drive the grain raised by the stone picker downward, and a yielding closure mounted in and partially closing the opening through which the grain is introduced, and a receptacle adapted to receive the foreign material driven from the grain said receptacle having an open side closed by a yielding member adapted to be struck by such material and moved thereby to permit the material to enter the compartment.
6. A stone picker, adapted to remove foreign material from the stream of grain, which includes a rotating member mounted in the path of the grain and adapted, as it is rotated, to drive the foreign material from the stream of grain, and a yielding closure mounted in and partially closing the opening through which the grain is introduced, and a receptacle adapted to receive the foreign matter driven from the grain, said receptacle having an open side closed by a yielding member adapted to be struck by such material and moved thereby to permit the material to enter the compartment, and a deflector against which the material may strike, said deflector being adapted to deflect material against such yielding member, the resistance of the yielding member being such that grain striking it will not move it and heavier foreign matter striking it will move it sufficiently to pass into the receptacle.
7. A stone picker, adapted to remove foreign material from the stream of grain, which includes a rotating member mounted in the path of the grain and adapted, as it is rotated, to drive the foreign material from the stream of grain, in combination with a beater adapted to drive the grain raised by the stone picker downward, and a yielding closure mounted in and partially closing the opening through which the grain is introduced, and a receptacle adapted to receive the foreign material driven from the grain, said receptacle having an open side closed by a yielding member adapted to be struck by such material and moved thereby to permit the material to enter the compartment, and a deflector against which the material may strike, said deflector being adapted to deflect material against such yielding member, the resistance of the yielding member being such that grain striking it will not move it and heavier foreign matter striking it will move it sufficiently to pass into the receptacle.
8. In combination with a separator, a stone picker adapted to remove foreign material from the stream of grain, which includes a rotating member mounted in the path of the grain and adapted, as it is rotated, to drive the foreign material from the stream of grain, in combination with a beater adapted to drive the grain raised by the stone picker downward, and a yielding closure mounted in and partially closing the opening through which the grain is introduced, and a receptacle adapted to receive the foreign material driven from the grain, said receptacle having an open side closed by a yielding member adapted to be struck by such material and moved thereby to permit the material to enter the compartment, and a deflector against which the material may strike, said deflector being adapted to deflect material against such yielding member, the resistance of the yielding member being such that grain striking it will not move it and heavier foreign matter striking it will move it sufficiently to pass into the receptacle.
9. A stone picker adapted to remove foreign material from a stream of grain, which includes a rotating member mounted in the path of the grain and adapted, as it is rotated, to drive the foreign material from the stream of grain, in combination with a receiving compartment adapted to receive such material, said compartment having an open side closed by a yielding member adapted to be struck by such material and moved thereby to permit the material to enter the receiving compartment, and a deflector against which the material may strike, said deflector being adapted to deflect material against such moving member, and a second yielding closure mounted in the opening through which the stream of grain is introduced, and a beater mounted in rear of said stone picker and above it and adapted to force down grain raised by it.

10. In combination with a separator a stone picker adapted to remove foreign material from a stream of grain, which includes a rotating member mounted in the path of the grain and adapted, as it is rotated, to drive the foreign material from the stream of grain, in combination with a receiving compartment adapted to receive such material, said compartment having an open side closed by a yielding member adapted to be struck by such material and moved thereby to permit the material to enter the receiving compartment, and a deflector against which the material may strike, said deflector being adapted to deflect material against such moving member, and a second yielding closure mounted in the opening through which the stream of grain is introduced, and a beater mounted in rear of said stone picker and above it and adapted to force down grain raised by it.
11. In combination with a separator having a separating cylinder and a conveyor adapted to convey material thereto, a stone picker mounted between the two, in the path of the material fed by the conveyor, said stone picker adapted when it is rotated to drive the foreign matter upward, in combination with a beater adapted to force the grain raised by the stone picker down again in the direction of the cylinder, and a receiving compartment for the foreign material having an open side with a yielding closure mounted therein, in combination with a deflector against which material driven from the stone picker may strike and from which it will be deflected against the yielding closure, displace it and pass into the stone receptacle, the threshing cylinder being directly driven, the beater and stone picker being driven from the threshing cylinder, and the conveyor being driven from a shaft driven by the beater shaft.
12. In combination with a separator having a separating cylinder and a conveyor adapted to convey material thereto, a stone picker mounted between the two, in the path of the material fed by the conveyor, said stone picker adapted when it is rotated to drive the foreign matter upward, in combination with a beater adapted to force the grain raised by the stone picker down again in the direction of the cylinder, and a receiving compartment for the foreign material having an open side with a yielding closure mounted therein, in combination with a deflector against which material driven from the stone picker may strike and from which it will be deflected against the yielding closure, displace it and pass into the stone receptacle, and a second yielding closure over the conveyor, yieldingly closing the opening through which the grain passes, the threshing cylinder being directly driven, the beater and stone picker being driven from the threshing cylinder, and the conveyor being driven from a shaft driven by the beater shaft.
13. In combination with a separator having a separating cylinder and a conveyor adapted to convey the material thereto, a stone picker mounted between the two, in the path of the material fed by the conveyor,
- said stone picker adapted when it is rotated to drive the foreign matter upward, in combination with a beater adapted to force the grain raised by the stone picker down again in the direction of the cylinder, and a receiving compartment for the foreign material having an open side with a yielding closure mounted therein, the threshing cylinder being directly driven, the beater and stone picker being driven from the threshing cylinder, and the conveyor being driven from a shaft driven by the beater shaft.
14. In combination with a separator having a separating cylinder and a conveyor adapted to convey material thereto, a stone picker mounted between the two, in the path of the material fed by the conveyor, said stone picker adapted when it is rotated to drive the foreign matter upward, in combination with a beater adapted to force the grain raised by the stone picker down again in the direction of the cylinder, and a receiving compartment for the foreign material having an open side with a yielding closure mounted therein, in combination with a deflector against which material driven from the stone picker may strike and from which it will be deflected against the yielding closure, displace it and pass into the stone receptacle, the threshing cylinder being directly driven, the beater and stone picker being driven from the threshing cylinder, and the conveyor being driven from a shaft driven by the beater shaft.
15. In combination with a separator having a separating cylinder and a conveyor adapted to convey material thereto, a stone picker mounted between the two, in the path of the material fed by the conveyor, said stone picker adapted when it is rotated to drive the foreign material upward, in combination with a beater adapted to force the grain raised by the stone picker down again in the direction of the cylinder, and a receiving compartment for the foreign material having an open side with a yielding closure mounted therein, in combination with a deflector against which material driven from the stone picker may strike and from which it will be deflected against the yielding closure, displace it and pass into the stone receptacle, and a second yielding closure over the conveyor, yieldingly closing the opening through which the grain passes, the threshing cylinder being directly driven, the beater and stone picker being driven from the threshing cylinder, and the conveyor being driven from a shaft driven by the beater shaft.

Signed at Battle Creek, county of Calhoun, and State of Michigan, this sixth day of March, 1925.

WAYNE H. WORTHINGTON.
